UNITED STATES PATENT OFFICE.

LOYD SCRUGGS, OF ST. LOUIS, MISSOURI, ASSIGNOR TO THE COPPER CLAD MALLEABLE RANGE COMPANY, OF ST. LOUIS, MISSOURI, A CORPORATION OF NEBRASKA.

STOVE-DOOR.

1,222,894.

Specification of Letters Patent. Patented Apr. 17, 1917.

Application filed October 27, 1913. Serial No. 797,549.

To all whom it may concern:

Be it known that I, LOYD SCRUGGS, a citizen of the United States, residing at St. Louis, Missouri, have invented a certain new and useful Improvement in Stove-Doors, of which the following is a full, clear, and exact description, such as will enable others skilled in the art to which it appertains to make and use the same.

10 This invention relates to stove doors, and particularly to stove doors of the type shown in my prior Patent No. 1,064,388, dated June 10th, 1913, wherein the hinges of the door are concealed.

15 The door shown in my said prior patent is provided with hinge members or arms that project inwardly through openings in the door frame, and said hinge members are provided at their inner ends with integral 20 stops or abutments that strike against the inside of the door frame, and thus limit the outward movement of the door when the door is opened. The openings in the frame through which the hinge members on the 25 door project are wider than said hinge members so as to permit the door to be moved laterally with relation to the frame, and thus bring the integral stops of said hinge members into alinement with portions of 30 said frame against which said stops strike. After the door has been positioned properly in the frame, a locking device is attached to the frame so as to prevent the door from moving laterally into an improper position, 35 or, in other words, from moving laterally far enough to carry the stops on the hinge members out of alinement with the portions of the frame against which said stops strike when the door is opened.

40 The object of my present invention is to provide a concealed hinge stove door that embodies all of the good features of the door shown in my said prior patent, but which can be manufactured at a lower cost 45 and assembled more easily.

To this end I have devised a stove door which is so constructed that it is not necessary to attach a locking device to the frame to hold the door in operative position.

50 Figure 1 of the drawings is a front elevational view of a portion of a cooking range whose warming ovens or compartments are equipped with concealed hinge stove doors constructed in accordance with my invention;

Fig. 2 is an enlarged perspective view of the door and the door frame looking at the inner side of said members;

Fig. 3 is a vertical sectional view taken through the door and a portion of the frame 60 so as to illustrate the position of the hinge members on the door when the door is closed; and

Fig. 4 is a similar view showing the door open.

Referring to the drawings which illustrate the preferred form of my invention, A designates a stove door whose lower edge portion is hinged to a door frame B. The door A is so proportioned that it laps over 70 the portions of the frame B adjacent the edges of the door opening in the frame, and the door is provided with hinge members which are so designed that they are completely concealed or hidden from view when 75 the door is in its closed position. In the form of my invention herein shown, the door is provided with hinge members 1, which consist of downwardly curved arms that project inwardly from the lower edge of the 80 door through openings in the door frame B. The hinge members 1 are provided on their under sides with curved surfaces that are preferably concentric with the point where the lower edge of the door terminates when 85 the door is in its closed position, and said curved surfaces coöperate with stationary hinge members 3 or curved surfaces on the door frame that are located at the lower edges of the openings 2 in the frame. When 90 the door is opened and closed the hinge members 1 on the door slide over the curved surfaces 3 on the door frame in the manner described in my said prior patent.

The frame B is provided at its upper side 95 with a hook 4 that coöperates with a lug 5 on the door to hold the door in its closed position, and as it is necessary to raise the door to disengage the lug 5 from the hook 4, when it is desired to open the door, I form 100 the openings 2 in the door-frame large enough to provide sufficient vertical play for the hinge members 1 on the door to permit the door to be raised bodily in a vertical plane when it is closed or nearly closed. 105 The inner end portions of the arms or hinge members 1 on the door are so proportioned that they correspond approximately to the depth or height of the openings 2 in the frame so as to eliminate excessive play or 110

lost motion between the coöperating hinge members on the door and door frame when the door is in its open position, as shown in Fig. 4. The outward movement of the door 5 is limited by means of stops 6 and 7 on the hinge members 1 that strike against stationary portions 8 on the frame B when the door is opened.

The width of the openings 2 in the frame 10 correspond approximately to the width of the hinge members 1 so as to prevent the door from moving laterally in either direction in relation to the frame B, and in the preferred form of my invention, as herein 15 shown, the openings 2 are in the form of open-ended slots that are formed in the inner edge portion of the frame B, so that one of the hinge members on the door can be slipped sidewise into its coöperating 20 opening in the frame during the operation of mounting the door in the frame, as hereinafter described. The vertical edges or 25 sides of the openings or slots 2 in the frame thus act as stops or abutments 9 which operate with the hinge members 1 on the door so as to prevent the door from moving laterally in either direction. One of the hinge members on the door is preferably provided with an integral stop 6, and the 30 other hinge member on the door is provided with a removable or detachable stop 7 herein shown as a screw that is screwed into the upper side of its coöperating hinge member adjacent the inner end of same.

35 In mounting the door, the hinge member 1 that is provided with the integral stop 6, is first slipped sidewise into its coöperating opening in the door frame, and the door is then moved inwardly toward the frame so 40 that the other hinge member thereon will enter its coöperating opening in the frame. The removable stop 7 is then arranged in operative position on its hinge member. While I prefer to provide one of the hinge 45 members on the door with an integral stop, and the other hinge member with a removable stop, it will, of course, be understood that the same result could be accomplished in other ways without departing from the 50 spirit of my invention.

The door is preferably provided with means which prevents the door from sticking or jamming in case a careless person pulls the door in the direction tending to 55 move the lower edge of the door upwardly and outwardly away from the door frame during the operation of closing the door, said means being the same as the means used for this purpose in my said prior patent, and consists of supplementary stops or 60 auxiliary stops 6^a on the hinge members 1, that project downwardly below the lower

edge of the openings 2 in the frame when the door is opened, as shown in Fig. 4.

From the foregoing it will be seen that 65 the door herein described embodies all of the good features of the door shown in my said prior patent, but it can be manufactured at a lower cost, and mounted in the door frame more easily, owing to the fact 70 that it is not necessary to attach a fastening device to the frame so as to prevent the door from moving laterally with relation to the frame, the door being prevented from moving laterally by means of the integral stops 75 or abutments 9 on the frame, which bear against the sides of the hinge members 1 on the door.

While I have herein shown my invention embodied in a stove door that swings about 80 a horizontal axis, it will, of course, be understood that my invention is applicable to a stove door that swings about a vertical axis.

Having thus described my invention, what 85 I claim as new and desire to secure by Letters Patent is:

A stove, comprising a door frame provided with a door opening, a pair of horizontally-disposed, open-ended slots formed 90 in the side edges of the opening in said frame diametrically opposite each other and adjacent the lower edge of said opening, a door provided at its lower edge with a pair of hinge members that project rearwardly 95 from the door through the slots in said frame, the outer side face of each of said hinge members bearing against the inner end of the slot through which said member passes, thereby preventing the door from 100 moving laterally in either direction with relation to the door frame, an integral stop on the inner end of one of said hinge members that bears against the inner side of the door frame when the door is open, and thus 105 prevents said hinge member from moving forwardly out of its slot, and a removable stop on the other hinge member that performs a similar function, the hinge member with the integral stop being adapted to 110 be inserted sidewise into its coöperative slot, and the other hinge member being adapted to have its end introduced in its slot and moved rearwardly through same prior to the operation of connecting the removable stop 115 to said hinge member.

In testimony whereof I hereunto affix my signature, in the presence of two witnesses, this twenty-third day of October, 1913.

LOYD SCRUGGS.
